SLACK OR CUTTINGS REMOVING ATTACHMENT FOR KERF-CUTTING MACHINES

Thomas E. Pray, Chicago, Ill., assignor to Goodman Manufacturing Company, Chicago, Ill., a corporation of Illinois

Application March 6, 1942, Serial No. 433,581

6 Claims. (Cl. 262—28)

This invention relates to improvements in slack or cuttings removing attachments for kerf-cutting machines of the room and pillar type, and has for its principal object to provide a relatively light, labor saving device of the character described, capable of easy attachment to or detachment from a kerf-cutting machine of conventional construction.

More particularly, my present invention relates to slack removing devices of the type broadly disclosed in my co-pending application, which has matured into Patent No. 2,278,796, issued April 7, 1942, wherein a conveyor of the continuous flight type is arranged to be driven from the power coupling usually provided for driving the transporting truck from the rear end of the mining machine.

The principal object of the present invention is to provide a simplified form of drive gearing and power coupling arrangement organized to afford an especially efficient, light, and readily detachable device for the intended purpose. A further object is to provide an attachment consisting of a plurality of parts which may be more conveniently handled for attaching or detaching the device relative to the kerf-cutting machine under the limited space conditions usually available in a mine.

The invention may best be understood by reference to the accompanying drawings, in which:

Figure 1 is a plan view showing the rear end of a kerf-cutting machine with a slack removing device constructed in accordance with my invention attached thereto, and with certain parts broken away and shown in horizontal section;

Figure 2 is an enlarged side view of the apparatus shown in Figure 1, with portions of the drive mechanism shown in longitudinal section;

Figure 3 is a transverse section taken on line 3—3 of Figure 2, but drawn to a slightly larger scale;

Figure 4 is a fragmentary side view showing the rear end of the kerf-cutting machine with the major part of the slack removing device removed so as to be loaded upon a transporting truck;

Figure 5 is an enlarged detail section taken on line 5—5 of Figure 1;

Figure 6 is an enlarged detail section taken on line 6—6 of Figure 2; and

Figure 7 is an enlarged detail section taken on line 7—7 of Figure 2.

Referring now to details of the embodiment of my invention illustrated in the drawings, the slack removing device indicated generally at A is shown as applied to a kerf-cutting machine of

the conventional room and pillar type, indicated generally at B, and comprising a main frame 10 having a chain-carrying cutter bar 11 projecting forwardly from said frame. Said cutter bar is supported in an underframe or cuttings channel disposed below said main frame between side walls 12, 12 and a base plate 13, said cuttings channel opening as usual to the rear end of the machine. The cutter chain 14 is driven from a chain sprocket 15 operatively driven as will presently be described, by a motor 16 disposed at the front of the frame. Flexible feeding means is also provided as usual, herein consisting of a pair of winding drums 17, 17 at opposite sides of the machine, suitably driven from the motor 16 and having flexible cables 18, 18 thereon adapted to be anchored at suitable points along the working face of the mine to feed the cutter bar to the coal.

Kerf-cutting machines of the character herein described are usually transported from place to place on a wheeled truck such as indicated generally at C in Figure 4, and while mounted on said truck, the latter is driven by power from the motor 16 of the kerf-cutting machine. For this purpose, the running gear of the truck C is connected as usual by suitable gearing to a tongue 19, which is adapted to be moved into operative engagement with a power take-off device at the rear end of the mining machine when the latter is mounted in transporting position on said track. The means for providing such power drive for the truck will more fully appear as the following description proceeds. It will be understood, however, that when the machine is to be used for cutting coal, it is entirely withdrawn from the truck and is moved over the mine floor on its own bottom by means of the cables 18, 18. Accordingly, the slack removing device is preferably designed for attachment to the rear end of the kerf-cutting machine only during actual cutting, and the major portion of said slack removing device is detached from the mining machine when the machine is loaded on its truck for transportation.

Referring now more particularly to details of the slack removing device A, which forms the subject matter of the present invention, said device includes an elongated frame 20 carrying a conveyor of the paddle type, herein consisting of a centrally disposed chain guide 21, having an endless chain 22 movable orbitally thereabout for carrying a plurality of horizontally disposed paddles 23, 23 along a bottom plate 24 extending at opposite sides of said chain guide to form a pair of troughs 25, 25. The frame 20 is adapted to be

supported at an upwardly and rearwardly inclined angle when attached to the kerf-cutting machine, and has a flattened front end portion supported on the rear end of the base plate 13 of said machine in position to receive the cuttings as they are discharged from the rear end of the cutter chain channel, as seen in Figures 1 and 2.

In the form shown, the bottom plate 24 has a supporting plate 26 secured beneath its forward, horizontal portion in position to abut the rear edge of the base plate 13 of the mining machine, while a forwardly rounded front end portion 24a of the bottom plate overlaps the edge of said base plate, as shown in Figures 1 and 2.

The lower or front end of the conveyer frame 20 is detachably mounted relative to the machine frame 10, as by hooks 21, 27 hinged on pivots 28, 28 on the outer sides of the troughs 25, 25, and extending forwardly to engage pins 29, 29 on the side walls 12, 12 of the mining machine underframe (see Figures 2 and 3).

The upper or rear end of the conveyer frame 20 is supported in its inclined position by a pair of links 30, 30 hinged on pivots 31, 31 at opposite sides of the troughs 25, 25 and extending forwardly to pivot pins 31a, 31a which are preferably mounted for ready detachment on brackets 32, 32 fixed on the rear end of the main frame 10 above the cuttings discharge opening.

The conveyer chain 22 passes around a drive sprocket 33 having suitable bearing on the flattened front end of the frame 20 as by means of an anti-friction bearing member 34 recessed within said sprocket and mounted on an upstanding annular bearing support 35 secured to the upper face of the bottom plate 24 (see Figure 2). At the upper rear end of the frame 20 the conveyer chain passes around an idler sprocket 36. The links of the conveyer chain 22 are of the usual universal or double pivoted type commonly employed in paddle type conveyers where, as here, the conveyer moves in an upwardly curved path.

An upright baffle plate 37 extends rearwardly and inwardly from one side wall 12 of the cuttings discharge passage so as to assist in directing the cuttings toward the conveyer paddles 23. In the form shown herein, a flexible extension 38 is connected to the rear end of said baffle plate and extends to a point closely adjacent the zone of swinging movement of said paddles, as shown in Figure 1.

The drive sprocket 33 for the conveyer chain is driven through an upright shaft 50 which is connected to the power take-off device on the mining machine, as will now be described.

As heretofore constructed the power take-off of conventional kerf-cutting machines has consisted of a socket member 40 fixed on the rear end of a shaft 41 extending through the rear end of the main frame 10. In the form of machine shown herein, the shaft 41 is supported in a bearing plate 42 at the rear end of the machine frame, and is driven from the motor 16 through suitable gearing (not shown). Said shaft also drives the cutter chain sprocket 15 of the machine through bevel pinion 43, bevel gear 44 on hub 45, and a sliding clutch member 46 on said hub, having selective engagement with a clutch ring 47 on sprocket shaft 48.

In providing a drive connection for the slack removing device from the power take-off socket

40 just described, I find it preferable to provide additional gear reduction for driving the conveyer chain 22. For this purpose a gearing attachment indicated generally at D is provided, to deliver power at reduced speed to the upright drive shaft 50.

In the preferred form shown, the gearing attachment D consists of a casing 51 adapted for detachable connection as a unit to the rear end 10 of the machine frame independently of the conveyer frame 20. Said casing has a lower part 52 having a vertically disposed bevel gear 53 rotatably mounted therein on its hub and a co-acting bevel pinion 54, rotatably mounted on the 15 rear end of a horizontal stub shaft 55, journaled in the forward portion of said casing. A spur gear 56 is fixed on the hub of said bevel pinion and is meshed with a spur gear 57 having an elongated hub 58. The latter hub is rotatably 20 mounted in a horizontally split bearing formed by a cover plate 59. Said hub has an extension shaft 60 fixed therein, which projects forwardly from the casing 51 and is provided with a rectangular head adapted to fit in the socket 40 of the power take-off. The gear 57 at the rear end of shaft 60 also has a socket 61 formed therein similar in shape to the socket 40. The cover plate 59 has a downwardly offset portion 62 with a rearwardly facing opening affording access to the socket 61. Accordingly, the gear 57 and shaft 60 form in effect an extension for the power shaft 41, for detachable connection with the tongue 19 of the truck, and also afford a driving connection for the slack removing device through the reduction gearing in casing 51.

The gearing attachment D may be suitably connected to the mining machine frame 10, as by bolts 64, 64 passing through flanges 65, 65 formed integrally with the casing 51 (see Figures 40 6 and 7). An auxiliary supporting bracket 66 may also be detachably connected to the main frame 10 below the casing 51, as shown in Figures 2 and 4.

The upright drive shaft 50 is preferably provided with a splined lower end 67 so as to be detachably fitted in a correspondingly splined socket 68 of drive sprocket 33. Said drive shaft is also provided with a splined upper end 69, adapted to be detachably fitted in a correspondingly splined socket 70 in the hub of bevel gear 53. It will also be observed that the socket 70 in gear 53 extends upwardly through said gear, and has a registering recess 71 in the offset portion 62 of the cover plate 59, so as to permit the lower end of shaft 50 to be raised out of engagement with the lower drive sprocket when desired. This arrangement permits the conveyer member A to be removed bodily from the machine B independently of the upper gearing attachment D.

The use and operation of the slack removing device above described will now be explained as follows: The conveyer frame 20 of attachment A is attached to the main frame of the mining machine B only at such times as said machine is dismounted from its transporting truck C, and preferably after the machine has been moved into cutting position relative to the working face of the mine. However, the gearing attachment D is preferably mounted permanently on the rear end of the mining machine so as to be carried with the latter even when it is mounted on its transporting truck as shown in Figure 4. In this case, the driving tongue 19 of the mining machine is driven through the extension

shaft 60 of the gearing attachment. The conveyer frame can be readily connected with or disconnected from said gearing attachment by manipulation of the upright drive shaft 50 and its splined end connections, as previously described. Thus the operator is required to handle but a part of the entire attachment and is relieved of lifting the substantial weight of the gearing attachment D in the relatively cramped and limited space conditions usually existing in mines.

When in use, the attachment serves to discharge the cuttings on the mine floor at a distance from the rear end of the cutting machine, so as to relieve the machine operator of the labor of shoveling away the cuttings. The attachment can also be employed advantageously in certain systems of mining using a loading conveyer disposed in close proximity along the working face, leaving only a limited space for operating the cutting machine between said loading conveyer and the mine wall. In such a system, the cuttings can be elevated and discharged directly into the loading conveyer.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. A cuttings removing device adapted for detachable connection with a kerf-cutting machine, comprising a rearwardly inclined frame having an endless orbitally movable conveyer chain with laterally extending gathering arms thereon, a horizontally rotatable drive sprocket for said conveyer chain mounted on a vertical axis at the front end of said frame, an upright drive shaft adapted for endwise detachable driving engagement in said sprocket, and coupling means adapted for detachable driving connection with a power driven coupling member on the kerf-cutting machine and affording endwise sliding connection with the upper end of said drive shaft, to permit said drive shaft to be raised out of driving engagement with said drive sprocket.

2. A cuttings removing device comprising a rearwardly inclined frame having an endless orbitally movable conveyer chain with laterally extending gathering arms thereon, a horizontally rotatable drive sprocket for said chain at the front end of said frame, a coupling support adapted for detachable connection with a kerf-cutting machine, an upright drive member and a horizontally disposed conveyer drive member adapted for connection with a power driven take-off member on said kerf-cutting machine, both rotatably mounted in said coupling support and having geared connection with each other, an upright drive shaft adapted for endwise detachable driving connection with said drive sprocket and having endwise slideable movement relative to said drive member, and means affording independent detachable connection of said

conveyer frame and said coupling support respectively, relative to said kerf-cutting machine.

3. A cuttings removing device comprising a rearwardly inclined frame having an endless orbitally movable conveyer chain with laterally extending gathering arms thereon, a horizontally rotatable drive sprocket for said chain at the front end of said frame, a coupling support adapted for detachable connection with a kerf-cutting machine, an upright drive member and a horizontally disposed conveyer drive member adapted for connection with a power driven take-off member on said kerf-cutting machine, both rotatably mounted in said coupling support, and gear reduction mechanism to drive said upright drive member at a reduced speed, an upright drive shaft affording endwise detachable driving connection between said drive member and said drive sprocket, and means affording independent detachable connection of said conveyer frame and said coupling support respectively, relative to said kerf-cutting machine.

4. A cuttings removing device comprising an elongated rearwardly inclined frame carrying an endless paddle-type conveyer chain, a drive sprocket for said chain at the forward end of said frame, means affording detachable connection of said frame in cuttings-receiving relation with a kerf-cutting machine, a coupling support having a rotatable coupling member adapted for connection with a power-driven take-off member on said kerf-cutting machine to form an extension of said take-off member, and an upright drive shaft affording endwise detachable connection between said drive sprocket and said coupling member so as to permit detachment of said conveyer frame relative to said kerf-cutting machine without disturbing said coupling support.

5. A cuttings removing device comprising a rearwardly inclined conveyer adapted for detachable connection at its forward end in cuttings-receiving relation with a kerf-cutting machine, drive means for said conveyer including an upright drive shaft at the forward end of said conveyer, a coupling support for independent connection to the rear end of said kerf-cutting machine, said coupling support having an upright rotatable socket member adapted to be driven by a power take-off member on said kerf-cutting machine, said upright shaft having endwise detachable driving connection at its upper end in said socket member.

6. A cuttings removing device comprising a rearwardly inclined conveyer adapted for detachable connection at its forward end in cuttings-receiving relation with a kerf-cutting machine, a drive sprocket for said conveyer disposed on a vertical axis at the front end of said frame, a coupling support adapted for independent connection with the rear end of said kerf-cutting machine in spaced relation above said conveyer, and having a rotatable socket member adapted to be driven by a power take-off on said kerf-cutting machine, and an upright drive shaft having its lower end detachably mounted in said drive sprocket, and its upper end detachably mounted in said socket member.

THOMAS E. PRAY.
